UNITED STATES PATENT OFFICE.

OLIN H. BASQUIN, OF CHICAGO, ILLINOIS, ASSIGNOR TO THE LUXFER PRISM PATENTS COMPANY, OF SAME PLACE.

ADJUSTABLE PRISM-CANOPY.

SPECIFICATION forming part of Letters Patent No. 586,223, dated July 13, 1897.

Application filed April 20, 1897. Serial No. 632,983. (No model.)

To all whom it may concern:

Be it known that I, OLIN H. BASQUIN, a citizen of the United States, residing at Chicago, in the county of Cook and State of Illinois, 5 have invented an Adjustable Prism-Canopy, of which the following is a description.

My invention relates to a device for adjustably holding prism-canopies. These prism-canopies consist of comparatively heavy 10 prism-lights assembled together to form a prism-plate, and this prism-plate is intended to be mounted outside the window or aperture through which the light is to be introduced. In the ordinary use of such a canopy 15 it is evident that it must be moved in and out, or, in other words, folded against the window or projected therefrom. Moreover, it is very desirable that it be so constructed and mounted that it can be readily adjusted from time 20 to time to vary its inclination and thus control to a degree its action. It is also highly desirable that such a prism-plate should be so mounted that when in actual use for introducing light it will leave a space at the 25 upper part of the window for ventilation. Since in many instances the prism-plate is preferably of substantially the same length as the window, it will be seen that this necessitates mounting the prism-plate in such a 30 way as to cause the upper end of the prism-plate to descend when the plate is extended. There are other features in a construction of 35 this general nature highly important to be accomplished, and they will be hereinafter more fully referred to.

My device is illustrated in the accompanying drawings, wherein—

Fig. 1 is an elevation of a prism-plate mounted and in a substantially vertical position. Fig. 2 is a similar view, the plate being inclined. Fig. 3 is a cross-section, the parts being shown in substantially the relation of Fig. 2. Fig. 4 is a detail of the pivotal supporting part; Fig. 5, the same from a 45 different point of view; Fig. 6, an elevation of this with other associated parts; Fig. 7, a detail of the lower supporting parts; Fig. 8, a detail of the arm connection; Figs. 9 and 10, details of the lower rail and eye for controlling the device.

Like parts are indicated by the same letter in all the figures.

A A are the surrounding portions of the window-frame. B is a prism-plate associated therewith, preferably as nearly as possible of 55 substantially the same width as the window-opening. This prism-plate is associated with two arms C C, one on each side, each pivoted at the point D to the window-frame, and also pivoted at a point E to the side bar F of the 60 prism-plate B.

The side bars F F of the prism-plate are joined at G to the cross-bar H, which, together with the side bars and the lower end bar, form the frame of the prism-plate. The 65 cross-bar H is turned over at J and pivoted at K by the antifriction-rollers in the channel-bars L. The distance from the pivot-point K to the pivot-point E is equal to the distance from E to D, and each of these distances is substantially equal to one-fourth of 70 the entire length of the prism-plate.

N is the lower frame-piece of the prism-plate.

The pivot-points or rollers K K are adapted 75 to roll up and down in the channel-bars L, so that the frame at that end is pivoted, but on a movable pivot. These channel-bars are held in position on the frame and in proper relation to each other by the screws M M, being shaped as indicated in Fig. 6, so that the bent portion J of the top bar H passes between the two portions of such channel-bars. Since the pivot-point D is fixed and the pivot-points K K are movable, it is evident that the 80 prism-plate B may be inclined more or less, and since the distances from the pivot E to the pivots K and D are the same the center of gravity or the middle point of the plate B will move back and forth in a horizontal line, 85 or, in other words, the prism-plate is so supported that its center of gravity when it is swung to different inclinations travels on a horizontal line, and therefore there is the least possible friction on the parts, the plate will 90 stay in any desired position, and the plate can be minutely adjusted. At the lower end of the plate and on the cross-bar M is secured the eyepiece N, whereby the plate can be drawn in or out. Since the upper end of the prism- 95

plate is free to move in a vertical line, it will, when extended, as shown in Fig. 3, leave a space at the upper part of the window for ventilation.

5 There are many localities in which buildings are lighted by artificial light where it is possible to light them by the light from the sky, and this can be done by the use of the prisms; but in so doing under ordinary conditions the result is to close up the windows by the prism-plates, so that while the heat of the light disappears when the lights are extinguished the room is nevertheless put into an unsatisfactory condition by the confinement of the air by a closed window. A prism-canopy like that here illustrated, which moves vertically and also as to its angle of inclination, avoids these difficulties, for it introduces the light, while at the same time 15 permitting a very great degree of air circulation and ventilation.

These prism-plates are made up of prism-lights or small sections of a practically uniform size, usually about four inches square, 20 though the size may be varied. Evidently when they are to be applied to a window a certain amount of difficulty arises from the fact that the prism-lights, having a uniform width, cannot be worked into groups which will exactly fit the windows. They must always be a little less, and the differences in width will vary through a range nearly equal to the width of an individual prism-light. To avoid the difficulties which would result from these 25 conditions, I have devised the form of frame for the prism-light herein illustrated, the top bar being, as it were, separable from the remainder of the frame. This bar having been made of proper size to fit the window, and 30 with its pivot-rollers in the channel-bars on opposite sides, can then be used as a support for the frame, the side bars of the frame being secured thereto midway, so that the prism-plate will hang in the middle of the window

with half of the unoccupied space on each side. The several obstructing parts of the arms and supporting parts are cut away, as indicated, for example, in Fig. 8, so as not to interfere with the prisms on the prism-plate, and the prism-plate is supported on the bars 35 curved at J, as indicated, so as to throw the body of the prism back or outward from the window, and thus relieve the inwardly-projecting prisms from the danger of striking against the various parts of the window. A prism-plate of this character requires frequent and minute adjustments. Thus when put in proper position for the sun at a given angle or at a given time of day or at a given season of the year or with a given degree 40 of exterior illumination or for a given degree of interior illumination it is quite obvious that it must be changed in position to give the same result under varying conditions or a new result under the same conditions. Thus it is evident at once that there may be an almost infinite number of variations, every one of which is useful and important.

These prism-plates are of course very heavy 45 and unwieldy and must be handled by women and children, and hence must be supported so as to be most conveniently controlled. All these necessities and more have been considered in the production of this invention. 75

I claim—

A plate supported at its upper end by vertically-moving pivots in combination with supporting-arms which are approximately one-quarter the length of the plate, are pivotally secured at a fixed point below the moving pivot, and are also pivoted to the plate at a distance from its upper end approximately equal to one-quarter of its length. 80

OLIN H. BASQUIN.
